UNITED STATES PATENT OFFICE.

JOHN IANSON CREIGH, OF SHEFFIELD, ENGLAND, ASSIGNOR OF ONE-THIRD TO CAMMELL LAIRD & COMPANY LIMITED, AND ONE-THIRD TO JAMES McNEAL ALLAN, BOTH OF SHEFFIELD, ENGLAND.

HYDRAULIC PRESS AND THE LIKE.

Application filed July 3, 1922. Serial No. 572,637.

To all whom it may concern:

Be it known that I, JOHN IANSON CREIGH, a subject of the King of England, residing at Sheffield, in Yorkshire, England, have invented certain new and useful Improvements in or Relating to Hydraulic Presses and the like, for which I filed an application for patent in Great Britain on the 13th July, 1921; and I do hereby declare that the following is a full, clear, and exact description of the same.

This invention relates to hydraulic presses and the like, its object being to provide improvements in the control thereof by the provision of means for mechanically operating the various valves in correct sequence and automatically in the requisite stages to give the desired result.

According to the present invention a cam shaft is provided with a series of cams each having an operative connection with a valve of the press or like hydraulic machine and adapted to operate it in the required sequence on the rotation of the shaft from a suitable source of power. Means are provided for applying such power to the cam shaft and for automatically removing it at the end of a cycle of operations.

In the preferred construction a pulley or gear wheel is continuously rotated on the cam shaft, and a spring controlled key is provided movable about its own axis in a keyway of the cam shaft, the key being shaped and disposed to engage and disengage a keyway in the hub of the pulley by movement about its own axis. An arm is fitted or formed on the key and is accessible outside the cam shaft and a stop in the path of the arm is capable of being moved out of that path to enable the key to be turned into an operative position by its spring, and of being returned into that path to move the key back into an inoperative position. The key is conveniently mounted in bearings carried by collars which are secured to the cam shaft one on each side of the pulley or gear wheel. A sectoral recess or slot is formed in one collar for the arm of the key and a spring engaging the arm and tending to turn the key into an operative position is fitted to that collar. The stop in the path of the arm of the key is preferably provided by one limb of a bell crank

lever or the like which is movable about its pivot by an operating pedal or handle which may conveniently be connected to the other limb of the bell crank lever by an arrangement of links and levers, whereby the bell crank lever may be turned about its pivot to remove the stop from the path of the key arm and may be returned automatically by a weight or spring.

In the accompanying drawings:

Figure 1 is an elevation of apparatus according to the present invention.

Figure 2 is a sectional end view of Figure 1.

Figure 3 is a plan of Figure 1 and Figure 4 is a diagram showing the parts in the driving position.

Like reference numerals indicate like parts throughout the drawings.

In carrying out the present invention the various valves (not shown in the drawings), of the hydraulic press or the like are arranged in line and a cam shaft 1 is mounted in suitable bearings 2 parallel with and adjacent to the valves. The cam shaft 1 is furnished with a series of cams 3 each capable of operating one valve conveniently through a suitable lever 4. The various cams 3 are disposed at the requisite angle in relation to one another to operate their respective valves in the correct sequence, one complete revolution of the cam shaft thus successively operating all the valves.

The cam shaft 1 is rotated from any suitable source of power and means are provided for enabling the power to be applied at will and to be automatically removed at the desired stage in the press operation.

In the construction illustrated power is applied to a pulley 5 which is normally free to rotate on the cam shaft 1. A keyway 6 (Figure 4) is formed in the cam shaft 1 having a transverse section which is an arc of a circle, preferably less than a semi-circle. A key 7 is fitted in this keyway in which it may partially rotate, the key being mounted in bearings carried by collars 8 and 9 which are secured to the cam shaft 1, one on each side of the hub 10 of the pulley 5 (Figure 1). The key 7 is so shaped and disposed that in its normal or inoperative position as shown in Figure 2, the pulley 5 is free to rotate, but when the key 7 is partially ro-

tated about its own axis from the position shown in Figure 2 into that shown in Figure 4, one edge thereof will project out from the keyway 6 and engage a keyway 11 (of which there are conveniently six) in the hub 10 of the pulley thereby enabling the pulley to rotate the cam shaft.

The key 7 is provided with a suitable arm 12 and is spring-controlled as shown at 13, 10 the spring tending to rotate the key about its own axis into its operative position. Conveniently the arm 12 is disposed in a sectoral recess or slot 14 in the collar 8, the radial sides of this recess thus limiting the rotation of the key 7 about its own axis. The spring 13 is disposed in a suitable recess or angular bore of the collar 8 communicating with the sectoral recess 14. Normally the key is held in its inoperative position by the engagement of its arm 12 with a movable stop. Such a movable stop is constituted in the construction illustrated by one arm 15 of a bell crank lever 15, 16 suitably fulcrumed at 18 and linked at 19 to a spring-controlled 25 or counterweighted lever 20 capable of being lifted by the operating handle or pedal (not illustrated) through a link 21 and a bell crank lever or its equivalent 23, 24. The parts are so arranged that when this handle 30 or pedal is operated the limb 15 of the bell crank lever 15, 16 is removed from the path of and from contact with the arm 12 of the key 7 which will then be partially rotated about its own axis by the spring 13 when 35 one of the keyways 11 in the hub of the pulley wheel 5 arrives in the position to enable the key 7 thus to be rotated and to become operative. The cam shaft 1 will now be rotated and will operate the 40 valves of the press or the like in the sequence determined by the relative angular positions of the various cams 3. Towards the end of 45 one revolution of the cam shaft 1, which in this construction forms one cycle of operations, the movable stop 15, which will have been automatically returned to its original position shown in Figure 1 upon release of the operating handle or pedal will come into 50 contact with the arm 12, the outer end of which will thereby be prevented from continuing its movement around the axis of the cam shaft 1. The inner end of the arm 12 with the key 7 will, however, continue to move with the shaft 1, thereby causing the 55 key 7 to be turned about its own axis to its inoperative position and thus the power will be automatically cut off from the cam shaft 1 at the completion of one revolution thereof.

60 The link 19 is conveniently disposed in a slot formed in the face of a bracket 25 to which the bell crank lever 15, 16 is fulcrumed, and may be spring-controlled as indicated at 26 to hold it in contact with the 65 limb 16. If desired the bell crank lever 15,

16 may be dispensed with by extending the link 19 and arranging its end in the path of the arm 12 of the key 7.

To perform the press operation in two or more stages a corresponding number of 70 keys of like construction may be provided.

Any other means for applying power and for automatically cutting it off may be provided. For example, the pulley 5 or its equivalent may be rotated by worm gear 75 and the power be applied to the worm shaft by means of a belt shifter capable of shifting a belt from a loose to a fixed pulley thereon and vice-versa. The belt shifter would be spring-controlled and would be held against 80 the action of the spring when power was being applied to the cam shaft by a suitable catch capable of being released by a pin or like projection on the power wheel. With this construction the valves may be operated 85 in two or more stages by simply providing the required number of pins or like projections on the power wheel to trip the belt shifter catch.

What I claim is:—

1. In a hydraulic press or the like the combination of a cam shaft, a series of cams thereon each having an operative connection with a valve of the press and adapted to operate it in the required sequence on the 95 rotation of the shaft, a pulley or gear wheel on the cam shaft, means for rotating it from a source of power, a spring-controlled key movable about its own axis in a keyway of the cam shaft shaped and disposed to engage and disengage a keyway in the hub of the pulley by movement about its own axis, an arm on the key accessible outside the cam shaft, a stop in the path of the arm, means for moving the stop out of that path, and 100 means for returning the stop substantially as and for the purpose specified.

2. In a hydraulic press or the like the combination of a cam shaft, a series of cams thereon each having an operative connection 110 with a valve of the press and adapted to operate it in the required sequence on the rotation of the shaft, a pulley or gear wheel on the cam shaft, means for rotating it from a source of power, a spring-controlled key 115 movable about its own axis in a keyway of the cam shaft shaped and disposed to engage and disengage a keyway in the hub of the pulley by movement about its own axis, an arm on the key, a collar secured on the cam shaft at each side of the pulley or gear wheel thereon, bearings for the key carried by the collars, a sectoral recess in one collar for the key arm, a spring engaging the arm and tending to turn the key into an operative 120 position, a stop in the path of the arm, means for moving the stop out of that path, substantially as and for the purpose specified.

3. In a hydraulic press or the like the 130

- combination of a cam shaft, a series of cams thereon each having an operative connection with a valve of the press and adapted to operate it in the required sequence on the 5 rotation of the shaft, a pulley or gear wheel on the cam shaft, means for rotating it from a source of power, a spring-controlled key movable about its own axis in a keyway of the cam shaft shaped and disposed to engage and disengage a keyway in the hub of the 30 pulley by movement about its own axis, an arm on the key, a collar secured on the cam shaft at each side of the pulley or gear wheel thereon, bearings for the key carried by the 35 collars, a sectoral recess in one collar for the key arm, a spring engaging the arm and tending to turn the key into an operative position, a bell crank lever having one limb in the path of the arm of the key and means 40 operatively connected to the bell crank lever whereby it may be turned about its pivot to remove the limb from the said path and be returned automatically, substantially as and for the purpose specified.
- 20 4. In a hydraulic press or the like the combination of a cam shaft, a series of cams thereon each having an operative connection with a valve of the press and adapted to operate it in the required sequence on the 25 rotation of the shaft, a pulley or gear wheel
- on the cam shaft, means for rotating it from a source of power, a spring-controlled key movable about its own axis in a keyway of the cam shaft shaped and disposed to engage and disengage a keyway in the hub of the 30 pulley by movement about its own axis, an arm on the key, a collar secured on the cam shaft at each side of the pulley or gear wheel thereon, bearings for the key carried by the 35 collars, a sectoral recess in one collar for the key arm, a spring engaging the arm and tending to turn the key into an operative position, a bell crank lever having one limb in the path of the arm of the key and means 40 operatively connected to the bell crank lever whereby it may be turned about its pivot to remove the limb from the said path and be returned automatically substantially as and for the purpose specified.

In testimony whereof I hereunto affix my 45 signature.

JOHN IANSON CREIGH.
